CLAIM

The ornamental design for a cornbread baking dish, as shown and described.

DESCRIPTION

FIG. 1 is a top perspective view of a cornbread baking dish which illustrates my new design;

FIG. 2 is a top plan view thereof;

FIG. 3 is a right side elevational view thereof, the left side elevational view being a mirror image thereof;

FIG. 4 is a front elevational view thereof;

FIG. 5 is a bottom plan view thereof; and,

FIG. 6 is a rear elevational view thereof.
